UNITED STATES PATENT OFFICE

167,555

FLOWER POT STAND OR SIMILAR ARTICLE

Victor H. Bisharat, Berkeley, Calif.

Application October 20, 1951, Serial No. 17,028

Term of patent 7 years

(Cl. D35—3)

To all whom it may concern:

Be it known that I, Victor H. Bisharat, a citizen of the United States of America, residing in Berkeley, in the county of Alameda, and State of California, have invented a new, original, and ornamental Design for a Flower Pot Stand or Similar Article, of which the following is a specification, reference being had to the accompanying drawing, forming part thereof.

In the drawing:

Figure 1 is a perspective view of a flower pot stand or similar article, showing my new design, and

I claim:

The ornamental design for a flower pot stand or similar article, as shown.

VICTOR H. BISHARAT.
